MATERIAL DISINTEGRATING AND REMOVING APPARATUS

John D. Russell, Cranberry Township, Venango County, Pa., assignor to Joy Manufacturing Company, Pittsburgh, Pa., a corporation of Pennsylvania

Application August 29, 1950, Serial No. 181,977

13 Claims. (Cl. 262—9)

This invention relates to continuous miners, and more particularly to the material disintegrating and removing apparatus of such machines.

In a well-known type of continuous miner there is provided at the forward end of the same a material disintegrating and moving apparatus which is in the form of a frame about which there are caused to circulate in elongated, like orbits a series of disintegrating element-carrying chains, the upper runs of which travel outwardly with respect to the mine face under attack; and these chains not only act, with the forward portions thereof, to tear loose the coal or other mineral from the vein, but to convey it away from the face, through a distance of some feet, along the top of the disintegrating mechanism, and to discharge it into a flight conveyor which extends forwardly and downwardly from a point to the rear of the disintegrating apparatus to a position, at its forward end, below the level of the rearward end of the disintegrating apparatus and in such longitudinal relation to the latter that material discharged over the rearward end of the latter will be received and carried rearwardly by the flight conveyor. With such a disintegrating apparatus, a relatively large number of disintegrating elements must be used, they have little lateral flexibility, each must drag or tear loose the material in its path, and there is negligible opportunity for certain elements to position themselves automatically to take paths of least resistance and thus provide a set-up whereby succeeding elements may rip loose larger masses than would be present to be detached if each element had to tear through whatever lay in its restricted path of movement. Moreover, the element of vibration in the detachment of material is less than is possible when disintegrating elements having substantial lateral freedom of movement are provided as hereinafter described.

An object of the invention is to provide an improved disintegrating apparatus. Another object of the invention is to provide an improved disintegrating and material-moving apparatus adapted advantageously to replace the type of disintegrating apparatus of the multiple-chain type heretofore employed. A further object is to provide an improved mounting for disintegrating elements. Still another object is to provide an improved arrangement of disintegrating devices and of material receiving devices for the effective detachment and rearward conveying of mineral from a vein. A further object is to provide an improved driving arrangement for cooperating vein-disintegrating and material moving devices. Other objects and advantages of the invention will subsequently appear.

In the accompanying drawings, in which one illustrative embodiment of the invention is shown for purposes of illustration:

Fig. 1 is a plan view of the forward end of a continuous miner in which the illustrative embodiment of the invention is incorporated;

Fig. 2 is a longitudinal vertical section on the plane of the line 2—2 of Fig. 1;

2

Fig. 3 is a transverse, vertical section on the plane of the line 3—3 of Fig. 2;

Fig. 4 is a fragmentary, enlarged sectional view on the same plane as Fig. 2, showing details of the mounting of a disintegrating element;

Fig. 5 is a fragmentary enlarged sectional view on the same plane as Fig. 3, showing details of the mounting of a disintegrating element; and

Fig. 6 is a transverse vertical section on the plane of the line 6—6 of Fig. 2.

Referring to the drawings, there will be noted at 1 the longitudinally reciprocable frame which is characteristic of certain well-known miners. This reciprocable frame, which is advanced to effect sumping and retracted to effect withdrawal of a disintegrating mechanism which is mounted thereon, herein supports a power driven flight conveyor 2 which receives disintegrated material from my improved disintegrating and material delivery apparatus and delivers it rearwardly to a hopper for delivery from the latter to a desired point. The frame 1 supports my improved disintegrating and disintegrated material-moving apparatus, which is generally designated 3, for swinging in vertical planes about an axis A, which lies in the same straight line with the axis of a shaft 4, which shaft is suitably journaled and driven. The disintegrating and disintegrated material-moving apparatus 3 comprises side frames or bars 7 and 8 fixedly connected together by transversely extending deck plates 9 and 10 and by reinforcing angle-like elements 11, the plates 9 and 10 and the angle-like elements being welded at their laterally opposite extremities to the side frames or bars 7 and 8. The deck plates 9 and 10 are respectively upper and lower, with respect to each other, and they are connected at their forward ends by an arcuate plate 13, which is also welded at its laterally opposite ends to the frames 7 and 8, and are further connected at their rearward ends by a pair of cylindrical tubular housing and conveyor chain-guiding members 14 and 15, these being spaced from each other at their adjacent ends and, at their mutually opposite ends spaced from the frames 7 and 8. The frames 7 and 8 correspond in structure to conventional cutter bars, and consist of main body portions 20 and, relatively adjustable with respect to said main body portions, front nose portions 21, and said frames have guiding grooves 22 about their margins in which chains 23 and 24 are adapted to circulate.

A flight conveyor 25, of the center-chain type, is being adapted to be circulated over the upper deck plate 9 and beneath the lower deck plate 10. It comprises a suitable chain 26 having spaced flights 27 secured to it. The chain is guided at its forward end by a guide roller 28 journaled on a shaft 29 fixed at its opposite ends to the side bars or frames 7, 8. The drive of the chain 26 will be later described. Above the forward end of the chain 26 is a generally triangular (in cross section) deflector device 30 for receiving material from portions of the disintegrating apparatus later to be described and causing its delivery to the rearwardly moving portion of the flight conveyor. This deflector device 30 is secured at its opposite ends to supporting slides 31 which carry the front nose portions 21, 21. It is therefore adjustable—with the nose portions 21—when the latter are adjusted. At the rear end of the flight conveyor 25 there is another intercepting device 32 for directing the material carried back by the flight conveyor chain 26. This device is mounted just above the conveyor 2 at the forward portion of the latter, being secured at its opposite ends to side frame members 33, 34 of a trough 35 in which the conveyor 2 travels, and being also secured to the upturned forward end 36 of a housing 37 for the conveyor 2. The apparatus 3 may be moved upwardly by mechanism such as is shown in my Patent No. 2,751,208, granted

June 19, 1956 and which includes chains 42, 42, cylinder and piston mechanisms 43, 43 fastened to the side frames 7, 8, and other devices not herein illustrated, but fully disclosed in said application.

Extending between the frames 7 and 8, and journaled in the frame 1, and suitably driven, is the shaft 4, above mentioned. This has a splined central portion 51, and carries, near the opposite ends of the splined portion 51, drive sprockets 52, which are adapted to drive the chains 23 and 24. At the middle of the splined portion and between the tubular elements 14 and 15 is a drive sprocket 53 for the chain 26 of the flight conveyor. Each of the sprockets mentioned, by reason of its splined connection with the shaft 4, is rotated by the latter. Sleeves 55 and 56 space the sprocket 53 from the sprockets 52. It will thus be apparent that the side chains 23 and 24 and the flight conveyor 25 are driven from the shaft 4, which is disposed with its axis of rotation in the same straight line with the axis A, as above pointed out.

The chains 23 and 24 are, except that they are more heavily and strongly constructed, shown as of the conventional lugged block and connecting link type commonly used as cutter chains, and comprise disintegrating element carrying lugged blocks 61 connected by connecting links 62 through pivot pins 63, and the blocks 61 carry replaceable disintegrating elements 65 suitably disposed to tear out the coal or other mineral over a width of several inches.

At the forward end of the disintegrating apparatus a cross shaft 71 extends between the nose portions 21 of the frames 7 and 8. This shaft rotatably supports, as by bearings 72, a hollow shaft 73, which is herein shown as carrying suitably laterally spaced sprocket portions 74, and as having fixed to it at its ends, as at 75, chain sprockets 76 about which the chains 23 and 24 pass. By this arrangement, the chains 23 and 24 constitute driving means for the sprocket portions 74. The several sprocket portions 74 have sprocket teeth 74' and each of these sprocket portions has a continuous loop L of disintegrating chain around it and held in position on it only by the engagement of the teeth 74' in the spaces between the ends of adjacent connecting links 76' and between the side flanges or portions 77 of disintegrating element carrying links or blocks 78. These latter links carry replaceable disintegrating elements 79. Pivot pins 80 connect the blocks 78 with the connecting links 76'. The side flanges 77 of the blocks 78 are spaced somewhat more widely than the thickness, transversely, of the sprocket teeth 74', and the circumferential thickness of the sprocket teeth 74' is less than the distance between the adjacent ends of the connecting links 76'. The overall length of the chain loops, measured along a circle passing through the axes of the pivot pins 80, also slightly exceeds the circumference of the pitch circle of the sprockets. Thus the disintegrating elements 79 held in the lugged blocks 78 are free to move laterally and also slightly in radial directions and to follow the easiest paths in the material under attack.

The trough 35 at its forward end is flanked by triangular, rearwardly converging, deflecting plate portions 81, 82, and 83, which serve to deflect material brought back by the side chains 23 and 24 and to guide it to the trough 35 above mentioned. Forwardly of these plate portions are openings 84, 84 through which the chains 23 and 24 pass as they move about the sprockets 52, 52. The intercepting device 32, which may be of built-up construction, has a downwardly, rearwardly sloping upper plate portion 86 which is cut away at its ends as at 87 to provide the openings 84, 84, and which has a forward edge 88 adjacent the rearward ends of the flight conveyor 25 and receiving material brought back by the latter.

From the foregoing description, the mode of operation of the illustrative embodiment of the invention will be understood. The shaft 4 is driven as hereinabove ex-

plained. Accordingly, the drive sprockets 52 are rotated and these cause the chains 23 and 24 to be circulated. The circulation of these chains effects rotation of the sprockets 76 and, accordingly, the tubular drive element 73 is rotated, turning with it the several sprocket portions 74. These are chain wrapped, as above explained, and, accordingly, the continuous loops of chains which are carried by the sprocket portions are caused, as it were, to circulate in orbits surrounding the axis of the shaft 71. All of the chains—the side chains 23 and 24 and the (herein four) chain loops L—cooperate in the forming, during the sumping operation, of an opening which is preferably formed at the bottom of the working face, and then as the disintegrating apparatus is swung upwardly the several chains tear off the coal which overlies them and is ahead of them in their path of upward movement. The coal torn loose and brought out by the side chains 23 and 24 is deflected by the plate portions 81, 82, 83 to the conveyor trough 35. The coal or other mineral detached by the disintegrating elements carried by the blocks 78 of the chain loops L is thrown into the path of movement of the flight conveyor 25, or else onto the top of the deflector 30 over which it is moved into the path of the flight conveyor 25. The sumping operation will desirably be terminated when it has proceeded to a distance approximately equal to, but which may be, depending on the construction of the parts, either slightly more or slightly less than, the diameter of the circles swept through by the disintegrating elements carried by the blocks 78. Because of the nature of the support of the chain loops L by the sprocket portions 74, it will be appreciated that there may be a substantial lateral motion of the disintegrating elements 79. These may thus, to an extent, choose their paths, within comparatively narrow limits, with the result that at times they may seek the path of least resistance, while at other times they will, through engagement with relatively large masses of undetached solid coal, tend to remove pieces of larger size than would be removed if the bits or disintegrating elements were confined relatively rigidly to predetermined paths.

It will be noted that the disintegrating elements on the loops L, and on the chains 23 and 24, are arranged in suitable "lacings" so that they cumulatively remove the coal or other mineral over a width equal to the full width of the forward portion of the disintegrating apparatus.

In addition to the other advantages mentioned of the "loose" support of the loops L on the sprocket portions 74, it will be appreciated that the increased range for vibratory movement of the bits carried by the loops L will promote the desired disintegrating operation. It will be understood that this looseness is not only a lateral looseness, as shown in Figs. 3 and 5, but also that there is a degree of looseness in a direction circumferentially of the sprocket portions 74, which permits not only a certain amount of play between the chain loops L and the sprocket portions circumferentially of the latter, but also a slight radial capacity for movement on the part of the elements 79. The "loose" support of the loops L on the sprocket portions, etc. is now being claimed in my copending application Serial No. 571,292, filed March 13, 1956. The location of the flight conveyor 25 essentially between the tops and bottoms of the bar portions 20, insures a very effective removal of the coal or other mineral detached by the disintegrating elements on the chain loops L, and provides also a very rugged construction of the disintegrating apparatus, and one which is vertically compact.

While there is in this application specifically described one form which the invention may assume in practice, it will be understood that this form of the same is shown for purposes of illustration, and that the invention may be modified and embodied in various other forms without departing from its spirit or the scope of the appended claims.

What I claim as new and desire to secure by Letters Patent is:

1. In combination, in a material-disintegrating and conveying apparatus, side bars having upper and lower edges and connected at their forward ends and pivotally mounted at their rearward ends for swinging movement, a drive shaft having its axis in the same straight line with the axis of such swinging movement and carrying three drive sprockets, two in line with said side bars and the third midway between said two, a shaft element rotatively supported at the end of the bars remote from said axis for rotation on an axis parallel to said first mentioned axis and midway between the upper and lower edges of said bars, chains driven by the sprockets in line with the side bars and guided on said side bars and connected in driving relation with said shaft element and carrying material disintegrating elements, a plurality of disintegrating elements supported by said shaft element and rotated by the latter, and a flight conveyor arranged in the space between said side bars and including a conveyor chain having opposite edges in adjacency to said side bars and engaging and driven by said third sprocket and having an idler disposed closely adjacent to and rearwardly of said shaft element at a fixed distance from the latter and carried by said bars between the upper and lower edges thereof.

2. In combination, in a material-disintegrating and conveying apparatus, side bars having at least substantially rectilinear upper and lower edges and connected at their forward ends and pivotally mounted at their rearward ends for swinging movement, a drive shaft having its axis in the same straight line with the axis of such swinging movement and carrying three drive sprockets, two in line with said side bars and the third midway between said two, a shaft element rotatively supported at the end of the bars remote from said axis for rotation on an axis parallel to said first mentioned axis and at least substantially midway between the upper and lower edges of said side bars, chains driven by the sprockets in line with the side bars and guided on said side bars and connected in driving relation with said shaft element and carrying material disintegrating elements, a plurality of disintegrating elements supported by said shaft element and rotated by the latter, and a flight conveyor arranged between said side bars and including at least one deck plate extending between said side bars in the space between the upper and lower edges of the latter and fixed to the latter and a conveyor chain movable over said deck plate and driven directly by said third sprocket and having an idler disposed rearwardly of and closely adjacent to said shaft element above the lower edges of said side bars.

3. In combination, in a material-disintegrating and conveying apparatus, side bars having upper and lower edges and connected at their forward ends and pivotally mounted at their rearward ends for swinging movement, a drive shaft having its axis in the same straight line with the axis of such swinging movement and carrying three drive sprockets, two in line with said side bars and the third midway between said two, a shaft element rotatively supported at the end of the bars remote from said axis for rotation on an axis parallel to said first mentioned axis and spaced similarly to the latter from the lower edge of said side bars, chains driven by the sprockets in line with the side bars and guided on said side bars and connected in driving relation with said shaft element and carrying material disintegrating elements, a plurality of disintegrating elements supported by said shaft element and rotated by the latter, said disintegrating elements having lateral play relative to said shaft element, and a flight conveyor arranged between said side bars and including a conveyor chain engaging and driven by said third sprocket and of a width to handle the material between said side bars and having

an idler disposed close to and rearwardly of said shaft element and at a fixed distance from the latter and disposed above the lower edges of said side bars.

5. In combination, in a material-disintegrating and conveying apparatus, side bars having upper and lower edges and connected at their forward ends and pivotally mounted at their rearward ends for swinging movement, a drive shaft having its axis in the same straight line with the axis of such swinging movement and carrying three drive sprockets, two in line with said side bars and the third midway between said two, a shaft element rotatively supported at the end of the bars remote from said axis for rotation on an axis parallel to said first mentioned axis, orbitally moving chains driven by the sprockets in line with the side bars and guided on said side bars and connected in driving relation with said shaft element and carrying material disintegrating elements moving in orbits determined by the orbits of said chains, a plurality of circular series of disintegrating elements supported by said shaft element and rotated by the latter in orbits of a diameter as great as the maximum width of the orbits of said material disintegrating elements, and a flight conveyor arranged between said side bars terminating at its forward end to the rear of the forward ends of said side bars and disposed between the upper and lower edges of the latter and including a conveyor chain engaged and driven by said third sprocket and having an idler disposed closely adjacent to and rearwardly of said shaft element above the lower edges of said side bars, said conveyor chain having for its guidance an upper deck plate fixed to said side bars and having its forward end close to a midpoint between the top and bottom edges of said side bars.

35. In combination, in a material-disintegrating and conveying apparatus, side bars having upper and lower edges and connected at their forward ends and pivotally mounted at their rearward ends for swinging movement, a drive shaft having its axis in the same straight line with the axis of such swinging movement and carrying a plurality of drive sprockets, two in line with said side bars, a shaft element rotatively supported at the end of the bars remote from said axis for rotation on an axis parallel to said first mentioned axis, chains driven by the sprockets in line with the side bars and guided on said side bars and connected in driving relation with said shaft element and carrying material disintegrating elements, a plurality of orbitally moving disintegrating elements supported by said shaft element and rotated by the latter, and a flight conveyor arranged between said side bars between the upper and lower edges of the latter and having an idler disposed rearwardly of said shaft element above the lower edges of said side bars and having a drive sprocket on and driven by said first mentioned shaft, said flight conveyor having a deflector device overlying its forward end and having a transversely horizontal upper edge in a plane substantially tangential to and disposed adjacent the orbits of said disintegrating elements which are supported by said shaft element and extended upwardly to a position above a transverse plane parallel to the upper edges of said side bars and bisecting the orbits of said disintegrating elements supported by said shaft element.

6. In combination, in a material-disintegrating and conveying apparatus, side bars having parallel upper and lower edges and connected at their forward ends and pivotally mounted at their rearward ends for swinging movement upon a horizontal axis, a drive shaft having its axis in the same straight line with the axis of such swinging movement and carrying a plurality of drive sprockets, two in line with said side bars, a shaft element rotatively supported at the end of the bars remote from said axis for rotation on an axis parallel to said first mentioned axis, chains driven by the sprockets in line with the side bars and guided in parallel rectilinear paths on

said side bars and connected in driving relation with said shaft element and carrying material disintegrating elements, a plurality of disintegrating elements supported by said shaft element and rotated by the latter, and a flight conveyor arranged between said side bars and substantially wholly within the space between the parallel upper and lower edges thereof and driven by said first mentioned shaft and having adjacent its forward end a rotatable idler disposed rearwardly of said shaft element and with its axis in fixed relation to and above the lower edges of said side bars and in a plane below the plane including the axes of said shaft and shaft element.

7. In combination, in a material-disintegrating and conveying apparatus, side bars having upper and lower edges and connected at their forward ends and pivotally mounted at their rearward ends for swinging movement upon a horizontal axis, a drive shaft having its axis in the same straight line with such horizontal axis and carrying a plurality of drive sprockets, one in line with one of said side bars, another in line with the other of said side bars, and at least one intermediate said one and said another, a shaft element rotatively supported at the end of said bars remote from said axis for rotation on an axis parallel to said first mentioned axis, driven sprockets one in line with one of said side bars and another in line with the other of said side bars and each rotatable on the axis of and connected in driving relation with said shaft element, chains driven by the drive sprockets in line with said side bars and engaging and connected in driving relation with said driven sprockets and carrying material disintegrating elements, said chains moving in orbits determined by said side bars and said drive and driven sprockets and comprising opposite semicircular portions and rectilinear portions spaced apart at one end by the diameter of one of said semicircular portions and at the other end by the diameter of the other semicircular portion, a plurality of disintegrating elements supported by said shaft element and rotated by the latter, and a conveyor arranged in the space between said side bars and driven by said at least one other drive sprocket and having an idler disposed rearwardly of said shaft element and having a supporting shaft supported at its opposite ends on said side bars against translatory movement relative to the latter, said supporting shaft being disposed within the vertical space enclosed within the path which a straight line extending between corresponding points in the orbits moves through as its ends traverse said orbits.

8. In combination, in a material-disintegrating and conveying apparatus, side bars having upper and lower edges and connected at their forward ends and pivotally mounted at their rearward ends for swinging movement upon a horizontal axis, a drive shaft having its axis in the same straight line with such horizontal axis and carrying a plurality of drive sprockets, one in line with one of said side bars, another in line with the other of said side bars, and at least one intermediate said one and said another, a shaft element rotatively supported at the end of said bars remote from said axis for rotation on an axis parallel to said first mentioned axis, driven sprockets one in line with one of said side bars and another in line with the other of said side bars and each rotatable on the axis of and connected in driving relation with said shaft element, chains driven by the drive sprockets in line with said side bars and engaging and connected in driving relation with said driven sprockets and carrying material disintegrating elements, said chains moving in orbits determined by said side bars and said drive and driven sprockets and comprising opposite forward and rearward semicircular portions of which the diameter of the forward one is at least as great as that of the rearward one and rectilinear upper and lower portions spaced apart at one end by the diameter of the forward one of said semicircular portions and at the other end by the diameter of the rearward one of said semicircular portions, a plurality of disintegrating ele-

ments supported by said shaft element and rotated by the latter, and a conveyor arranged in the space between said side bars and having upper and lower runs and driven by said at least one other drive sprocket and having an idler disposed rearwardly of said shaft element and having a supporting shaft supported at its opposite ends on said side bars against translatory movement relative to the latter and in a position maintaining the lower run of said conveyor above the paths of the outer ends of the chain-carried material disintegrating elements as the latter are moved by said chains forwardly.

9. In combination, in a material-disintegrating and conveying apparatus, side bars having upper and lower edges and connected at their forward ends and pivotally mounted at their rearward ends for swinging movement upon a horizontal axis, a drive shaft having its axis in the same straight line with such horizontal axis and carrying a plurality of drive sprockets, one in line with one of said side bars, another in line with the other of said side bars, and at least one intermediate said one and said another, a shaft element rotatively supported at the end of said bars remote from said axis for rotation on an axis parallel to said first mentioned axis, driven sprockets one in line with one of said side bars and another in line with the other of said side bars and each rotatable on the axis of and connected in driving relation with said shaft element, chains driven by the drive sprockets in line with said side bars and engaging and connected in driving relation with said driven sprockets and carrying material disintegrating elements, said chains moving said material disintegrating elements in orbits determined by said side bars and said drive and driven sprockets and comprising opposite semicircular portions and rectilinear portions spaced apart at one end by the diameter of one of said semicircular portions and at the other end by the diameter of the other semicircular portion, a plurality of disintegrating elements supported by said shaft element and rotated by the latter, and a conveyor arranged in the space between said side bars and driven by said at least one other drive sprocket and having an idler disposed rearwardly of said shaft element and having a supporting shaft supported at its opposite ends on said side bars against translatory movement relative to the latter, said conveyor having an orbit of movement having its lower edge substantially parallel to the lower edges of said bars and between said rectilinear portions.

10. In combination, in a material-disintegrating and conveying apparatus, side bars having upper and lower edges and connected at their forward ends and pivotally mounted at their rearward ends for swinging movement upon a horizontal axis, a drive shaft having its axis in the same straight line with such horizontal axis and carrying a plurality of drive sprockets, one in line with one of said side bars, another in line with the other of said side bars, and at least one intermediate said one and said another, a shaft element rotatively supported at the end of said bars remote from said axis for rotation on an axis parallel to said first mentioned axis, driven sprockets one in line with one of said side bars and another in line with the other of said side bars and each rotatable on the axis of and connected in driving relation with said shaft element, chains driven by the drive sprockets in line with said side bars and engaging and connected in driving relation with said driven sprockets and carrying material disintegrating elements, said chains moving said material disintegrating elements in orbits determined by said side bars and said drive and driven sprockets and comprising opposite semicircular portions and rectilinear portions spaced apart at one end by the diameter of one of said semicircular portions and at the other end by the diameter of the other semicircular portion, a plurality of disintegrating elements supported by said shaft element and rotated by the latter, and a

conveyor arranged in the space between said side bars and driven by said at least one other drive sprocket and having an idler disposed rearwardly of said shaft element and having a supporting shaft supported at its opposite ends on said side bars against translatory movement relative to the latter, said conveyor having an orbit of movement having its lower edge substantially parallel to the lower edges of said bars and between said rectilinear portions and an upper edge sloping upwardly and rearwardly relative to the upper edges of said bars and at all points below the tops of the latter.

11. In a mine vein disintegrating mechanism, swingable in vertical planes for dislodging mineral from a solid mine vein, the combination comprising a frame pivotally mounted at its rearward portion to swing in vertical planes between the floor and roof of a mine, a toothed disintegrating drum journaled on the outer portion of said frame to revolve about an axis parallel to the pivotal axis of said frame, said frame having parallel vertical side frame portions and a transverse portion extending between said vertical side portions rearwardly of said drum, said transverse portion having a plane top surface, said drum extending transversely between said vertical side portions, endless toothed side disintegrating chains journaled on said vertical frame portions for circulation in parallel vertical orbits and operatively connected to said drum for rotating the latter, drive shaft means coaxial with the frame pivot and operatively connected to said side chains for driving the latter, and endless conveying means guided for orbital circulation on said transverse frame portion intermediate said vertical side frame portions and having a top run moving rearwardly of said frame and inclined upwardly and rearwardly with respect to a longitudinal plane including the pivotal axis of said frame and the axis of drum rotation, said conveying means terminating at its forward portion rearwardly of said drum in adjacency to the lower rearward portion of said drum in fixed spacial relation with respect to the drum axis and said frame, said conveying means receiving disintegrated mineral discharged from the upper rearward portion of said drum in all angular positions of said frame about its pivot between the floor and roof, the top run of said conveyor moving rearwardly along said plane top surface for conveying the disintegrated mineral rearwardly of said frame, said plane top surface of said transverse frame portion cooperating with the inner side surfaces of said vertical side portions of said frame to provide a hopper-

like chamber becoming progressively larger in cross section as said conveying means inclines forwardly and downwardly toward said drum, said hopperlike chamber providing a storage space for receiving the disintegrated mineral discharged from said drum in all positions of said frame about its pivot, said top run of said conveying means moving the mineral stored within said hopperlike chamber rearwardly of said frame to discharge at the rear end of said frame.

10 12. A combination as set forth in claim 11 wherein said transverse frame portion comprises a deflector extending transversely of said frame rearwardly of and adjacent to the upper rearward portion of said drum, said deflector overlying the forward portion of said conveying means and extending across said hopperlike chamber beneath the top of said vertical side portions of said frame, said deflector rigidly secured at its ends to said vertical side frame portions, said deflector directing the disintegrated mineral discharged from said drum rearwardly and downwardly toward said conveying means.

15 13. A combination as set forth in claim 11 wherein said inclined top plane surface of said transverse frame portion is disposed above said plane which includes the pivotal axis of said frame and the axis of drum-rotation, 25 said transverse frame portion being rigidly united with said side frame portions, and the angular relation of said plane top surface being fixed with respect to said frame and the drum-axis and said hopperlike chamber being of a fixed volumetric capacity, in all angular positions 30 of said frame.
